UNITED STATES PATENT OFFICE.

NORMAN P. HARSHBERGER, OF CHICAGO, ILLINOIS.

ROOF COVERING.

Application filed March 12, 1923. Serial No. 624,314.

This invention relates to improvements in roof covering, and particularly to small sheets or shingles of asphalt or other pliable substances which may be used for the purpose of covering roofs. One of the objects of the invention is to impart to the roof when covered a pleasing appearance, and this object is carried out by producing certain deformations or figures in the sheets to be used for covering the roof. These figures may be made in various ways such as by cutting slits in the sheets and pressing portions of the material out of the plane of the sheet, or in some suitable manner changing certain portions of the sheets so as to give to the roof as a whole the appearance of having clearly defined figures or groups of figures, the groups forming squares, parallelograms, diamonds or the like. Another object of the invention is to change the exposed edges of the sheets so as to prevent injury and to improve the appearance thereof. Other objects of the invention will be apparent by a consideration of the accompanying drawings and the following description thereof.

Of the drawings, Fig. 1 is a plan view of several sheets of roof covering, which for convenience may be called shingles, laid as on a roof, and embodying features of my invention; Fig. 2 is an enlarged plan view of a portion of a shingle showing a certain figure such as is formed on the shingles shown in Fig. 1; Fig. 3 is a section along the line 3—3 of Fig. 2; Fig. 4 is a plan view of two shingles having modified forms of figures; Fig. 5 is an enlarged view of a portion of a shingle showing a figure similar to the figures of the shingles of Fig. 4; Fig. 6 is a section along the line 6—6 of Fig. 5; Fig. 7 shows modified forms of figures, the elements of which are somewhat similar to Fig. 4.

In providing coverings for roofs it is frequently desirable to form the covering of individual units such as are ordinarily called shingles, at the same time it is desirable to make these units much larger than the ordinary type of shingles, and when so made the appearance of the roof is not so pleasing as if the units were smaller, as the figures which appear on the roof from a distance are large and indistinct. Furthermore it is difficult to lay such shingles in rows accurately unless guiding means are provided for properly placing, the shingles without waste of time.

In order to provide an improved appearance and for expediting the laying of the shingles I have provided large shingles consisting of sheets or strips 11 which may be of any suitable length and width, and formed in the strips are certain figures 12. These figures may be formed in various ways, I prefer to form them by cutting slits 13, preferably in the form of crosses, through the sheet and then to force the tongues 14, in any suitable manner, out of the plane of the sheets. I form a plurality of these figures in the sheet extending away from and at an angle to one of the long edges of the strip, extending preferably about one-third of the distance across the strip, this being the portion of the strip which is exposed or which is not covered by the next higher row of strips 15; and in laying the strips 15 they are placed with the lower edges 17, resting against the raised portion of the innermost figure 12 of the underlying sheet 11. In a similar manner the sheet 16 rests against the innermost figures of the sheet 15. When the sheets are so changed by the formation of these figures and so laid on the roof, the roof has a very pleasing appearance, not only because of the beauty of the figures themselves, but because of the special configuration which they form. From a distance the group of figures which are exposed give the appearance of being edges of separate units. At the same time the innermost figures of the rows provide very convenient guiding means for laying the next row.

In order to provide for the abutting together of two units, such as the units 16 and 18, I form slits 19 in each end of each of the units so placed that the slits will register when the units are in position; and the tongues formed by these slits and the edges of the sheets are turned upwardly so as to conform in shape with the tongues of the figures 12. In this manner the exposed portion of the abutting end appears substantially the same as the exposed rows of complete figures.

As is well understood, with pliable shingles such as ordinary asphalt shingles, having portions exposed, there is a tendency for the exposed portions, especially the corners, to warp or bend upwardly. Hence, when exterior slits or slots are cut in the exposed edges of the shingle, so as to give the appearance of individual units, there is a tendency for the exposed portion, espe-

cially at the corners to bow upwardly due to warping or other causes. But with figures formed by the interior slits which I have provided there is no tendency of this upward bending of the exposed portions where these figures are formed.

It is to be understood that, although I have shown a definite number of figures and rows of figures in the sheet, yet the number of figures and the position thereof, or other features could be changed without departing from the spirit of my invention as disclosed by the claims herein; and this is true also with reference to the particular directions in which for convenience I have shown the rows to extend.

Fig. 4 shows a modified form of figure which comprises U-shaped slits 23 cut through the interior of the shingles, and the tongues 24 thus formed are bent upwardly from the plane of the shingles. This also gives a pleasing appearance to the surface of the shingles when laid; and the tongues also form guides for positioning the upper row of shingles, as the edges 25 thereof are slit under the upper tongues 24 in rows of figures. This not only makes a very definite stop for positioning the edges 25 of the shingles, but also the tongues 30 tend somewhat to prevent any warping tendencies of the exposed edges. The figures of the shingles are positioned so that, when the ends of two shingles abut the rows of figures will be similarly spaced. In this instance I have provided rows 27 of similar figures along the edges of the shingles so that the exposed edges will be more prominent and also so as to give to the edges of the exposed portion an appearance similar 40 to the rows of figures at right angles to the edges.

Fig. 7 illustrates another modification of the figures comprising rows 29 of double U-shaped tongues 30 formed by cutting U-shaped slits through the sheets and bending the tongues out of the plane of the sheets. This arrangement of the tongues gives a more prominent and broader appearance to the rows of figures, and gives a very pleasing 50 appearance to the shingles when laid as indicated; and the upper edges 31 of the upper tongues form a very convenient stop for positioning the lower edges 32 of the next row of shingles.

In order to transmit shingles of this nature from one point to another it is customary to pack them in bundles, and in order to reduce the space required, and also to protect the rows of figures from injury, I so 60 construct these figures that those of one shingle

can be projected upwardly into those of the adjacent overlying shingle of the bundle. Thus the figures 12 are pyramidal in shape and as the positions of the figures on the various shingles are alike the figures of one shingle will not only register with those of the overlying shingle when they are packed with the edges registering, but also the figures of the lower one will project into the respective figures of the overlying one, and less space will be required, and there will be less probability of the figures being deformed. In case of the tongues 24, I form the slits 23 so as to produce beveled edges 28 so that the tongues 24 more readily pass 75 into the spaces 29 of the overlying shingles. Similarly with the embossed figures 35, the portions 36 connecting the raised portions with the sheets are formed slanting, as indicated, so that the raised portion passes 80 freely into the spaces 37.

I claim as my invention:

1. An article of manufacture comprising a shingle having a plurality of raised figures on the interior portion thereof, said figures being grouped in rows extending an equal distance inwardly from adjacent one edge of the shingle.

2. An article of manufacture consisting of a roof shingle having a plurality of raised figures thereon, said figures being formed by cutting interior slits through said shingle and raising portions of the shingle between adjacent slits above the plane of the shingle.

3. An article of manufacture consisting of a roof shingle having a plurality of raised figures thereon, said figures being formed by cutting interior U-shaped slits through the shingle and raising the portions of the shingle between adjacent slits above the plane of the shingle to form raised tongues thereon.

4. An article of manufacture consisting of a roof shingle having a plurality of raised figures thereon, said figures being formed by cutting slits through said shingle and raising portions of the shingle between adjacent slits above the plane of the shingle, said slits being U-shaped and being grouped in double rows.

5. A plurality of shingles laid in rows on a roof, each of said rows having an exposed lower edge, and groups of figures formed on said exposed portion, said groups comprising raised figures extending from adjacent the exposed edge of one row to the exposed edge of the overlying row.

In testimony whereof, I hereunto set my hand.

NORMAN P. HARSHBERGER.
